UNITED STATES PATENT OFFICE

ARTHUR C. TOSKE, OF JACKSONVILLE, FLORIDA

CYLINDER BORING TOOL

Application filed April 29, 1932. Serial No. 608,287.

This invention relates to a tool for boring the ends of cylinders.

As is well-known to those skilled in the art the wall of a cylinder is gradually worn by the piston rings and where these rings stop in their movement the internal diameter of the cylinder remains unchanged with the result that ultimately there is produced an interior annular shoulder.

10 The present invention has for an object the provision of a hand-operated tool whereby the unworn end portion of the cylinder wall can be bored so as to make the diameter of the cylinder opening uniform throughout the length thereof.

15 It is another object to provide a simple, compact, and efficient tool of this character which can be adjusted readily to the internal diameter of the cylinder to be treated and can be regulated at will to vary the cut by the cutting tool forming a part of the device.

20 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

25 In the accompanying drawings the preferred form of the invention has been shown.

In said drawings:

30 Figure 1 is a plan view of a portion of a cylinder block showing the tool supported in the open end of the cylinder to be bored. Figure 2 is a transverse section through the cylinder looking toward the tool, a portion of the tool being broken away.

Figure 3 is a side elevation of the tool.

35 Figure 4 is an elevation showing the opposite side thereof, the tool being positioned in a cylinder ready for use.

Figure 5 is another elevation of the tool viewed substantially at right angles to Figure 4.

40 Figure 6 is a section through the tool

on line 6—6, Figure 1, the bit and its adjusting screw being shown in elevation.

Figure 7 is an elevation of a guide leg and its binding means.

Referring to the figures by characters of reference, 1 designates the body of a block preferably partly cylindrical and having a flat peripheral portion 2. Formed on this body adjacent to the center thereof is a hub 3 having an angular socket 4 adapted to receive a wrench 5 whereby the entire tool can be rotated bodily by hand.

An opening 6 extends downwardly through the body from the bottom of the socket and is in communication with an angular passage 7 opening through the periphery of body 1 at a point opposite the center of the flat surface 2. In this passage is slidably mounted a cutting tool in the form of a bit 8, the inner end of which is engaged by one end of an adjusting screw 9 which is screwed into the body 1 and extends perpendicularly from the flat surface 2. By means of this screw the cutting edge of the bit 8 can be projected any desired distance beyond the periphery of body 1 so as to cut to the desired depth.

45 A supporting tongue or guide 10 extends radially from the body 1 above the projecting end of the tool 8 and is adapted to rest on the cylinder block B when the tool is properly positioned in cylinder C.

Another passage 11 is formed in the body 1 and opens through the periphery thereof adjacent to and in advance of the tool 8. In this passage is slidably mounted a guide leg 12 having a small roller 13 at its outer end adapted to travel along the inner surface of the wall of cylinder C in advance of the cutting edge of cutter 8. This leg has a threaded stud 14 projecting therefrom through a slot 15 formed in body 1 and a clamping nut 16 engages the stud and is adapted to bind on the body so as to hold the leg against sliding movement after it has been adjusted longitudinally.

50 Passages 17 are formed in the body 1 and diverge from each other and from the passage 7, these passages 7 and 17 being dis-

90

95

100

posed substantially at angles of 120° to each other. Each passage has a leg 18 slideable therein, there being a pin 19 in the body 1 and in one side portion of each passage 5 17 for limiting the outward sliding movement of the leg in said passage. Each leg is cut away longitudinally as at 20 for sliding contact with its retaining pin 19.

A bolt 21 is detachably mounted in the 10 outer end portion of each leg 18 and mounted on each bolt below leg 18 is a guide roller 22 for rolling contact with the inner surface of cylinder C below the point where the cylinder is to be bored.

15 Mounted on each bolt 21 above leg 18 is an adjusting eccentric 23 providing a series of openings 24 concentric with bolt 21. Any one of these openings 24 is adapted to receive a locking pin 25 which is also insert- 20 able into an opening 26 in leg 18. Obviously by removing pin 25 and rotating the eccentric 23 in a clockwise direction, as in Figure 1, the leg 18 will be forced outwardly relative to body 1 a desired distance 25 after which pin 25 can be reinserted to hold the parts against retrograde movement.

It can be assumed that the cylinder C has become so worn that an annular interior shoulder S has been formed therein, near 30 one end. For the purpose of boring this end portion of the cylinder so as to obliterate the shoulder, the tool constituting the present invention is inserted into the cylinder. The eccentrics 23 are then rotated so 35 as to wedge between body 1 and the bolts 21 and shift the rollers 22 outwardly against the cylinders below the shoulder S. These eccentrics are then secured by pins 25. Thereafter leg 12 and roller 13 are adjusted 40 against the surface to be cut. Thus the tool will be held in the cylinder and will be supported on the block B by tongue 10 and those portions of the eccentrics lapping the block. The cutting bit is then adjusted longitudinally by screw 9 until its cutting edge 45 bites into the wall of the cylinder. As this edge is of a length equal to or greater than that of the surface to be bored, it will be apparent that when the tool is rotated by means of wrench 5 the cutting edge of the 50 bit will plow through the surface portion of the cylinder. The cutting bit can be fed outwardly as required so that ultimately the shoulder S will be obliterated and the cylinder will be of the same bore throughout 55 its length. The leg 12 and the roller 13 will also be adjusted outwardly as needed to maintain proper cooperation of the bit with the wall of the cylinder.

60 Obviously the sizes of the rollers can be varied and the proportions of the other parts can also be changed to meet the requirements of cylinders of different sizes.

What is claimed is:

65 1. A tool for boring the end portion of a cylinder, including a body, a cutting bit

adjustably carried by and projecting from the body for engagement with the cylinder area to be cut, means adjustably connected to the body and support in advance of the bit for movable contact with the area of the cylinder to be cut, legs slidably connected to the body, means carried thereby for movable contact with the cylinder outside the area to be cut, and adjusting means cooperating with the body and carried by the legs for direct engagement with the cylinder to support the tool within the cylinder and for adjusting the legs relative to the body.

2. A tool for boring the end portion of a cylinder, including a body, a cutting bit 80 adjustably carried by and projecting from the body for engagement with the cylinder area to be cut, means adjustably connected to the body and support in advance of the bit for movable contact with the area of the cylinder to be cut, legs slidably connected to the body, means carried thereby for movable contact with the cylinder outside the area to be cut, and means cooperating with the body and carried by the legs for 85 adjusting said legs relative to the body and supporting the tool within the cylinder, said means including an eccentric rotatably mounted on each leg and bearing against the body, and means cooperating with the eccentric and its leg for holding the eccentric against rotation.

In testimony that I claim the foregoing as my own, I have hereto affixed my signature.

ARTHUR C. TOSKE.
